OPENER FOR TEAR STRIP CONTAINERS

Albert Gehweiler, Spencer, Mass.

Application April 30, 1954, Serial No. 426,851

2 Claims. (Cl. 220—52)

This invention relates to new and improved opening devices for containers that are provided with tear strips, and the principal object of the invention resides in the provision of a key for receiving the tab of the tear strip, said key being mounted as the pintle of a hinged member including a pair of leaves, each leaf being provided with a guide means to engage the upstanding peripheral rim of the usual container of this type, whereby the device may be used on containers of many different sizes and accommodates itself automatically to the curvature thereof whether the same is circular or of another shape, and at the same time the construction provides for the automatic motion of the key itself radially outwardly of the container as the tear strip is wound on the key, in effect increasing the diameter thereof, to smoothly accommodate the action of tearing the strip and to prevent wedging of the key.

The invention also includes the provision of means for slipping the wound tear strip from the key, the new device not being disposable but may be used repeatedly with containers of many different sizes and shapes.

Other objects and advantages of the invention will appear hereinafter.

Reference is to be had to the accompanying drawings, in which—

Fig. 1 is a view in front elevation of a device according to the present invention;

Fig. 2 is a top plan view thereof showing the same in use;

Fig. 3 illustrates the device as it is initially applied to the tear strip of a container;

Fig. 4 is a plan view of the device as it appears in Fig. 3, with the container omitted;

Fig. 5 is a diagrammatic view illustrating the radial outward movement of the key as it winds up the tear strip;

Fig. 6 is a section on line 6—6 of Fig. 2;

Fig. 7 is a view of a modification; and

Fig. 8 is a view similar to Fig. 6 and showing a modification of the guide tab.

The present invention embodies as the main part thereof a pair of inter-pivoted or hinged members 10 and 12. These members are provided with hollow bosses or the like indicated generally at 14 which receive the key 16, the same being slotted at one end as at 18 to receive the tab of the tear strip and having a crank handle 20 at the opposite end for turning the same. Means such as pins or in-set washers 22 or any other convenient means may be utilized for maintaining the key 16 against extraction from the bosses 14. The hinged members 10 and 12 are recessed adjacent the slotted portion of the key so that the slot is fully exposed, as clearly shown in Fig. 1.

It will be seen that the members 10, 12 form the leaves of a hinge, the pintle of which is the key 16, and these leaves may be swung around in a back-to-back relationship as shown in Figs. 3 and 4 in order to form a handle for easily applying the key 16 to the tab 24 of a tear strip 25 for a container 26.

When the tab 24 has been inserted in the slot 18, the leaves 10 and 12 may be swung inwardly toward the container and contact the same at the exterior surface thereof as shown in Fig. 2. Each leaf 10 and 12 is provided with a guide 28 which is bent inwardly and downwardly

2

and takes over the peripheral upstanding rim 30 normally provided on containers of the class described.

With the device in the Fig. 2 position, the same may be then slightly held in position by one hand, although this is not necessary, while the crank 20 is rotated in a clockwise direction by the other hand and this will of course wind the strip from the can, opening the same as will be clear. At the same time, of course, the device travels around the can in the direction of the arrow in Fig. 2.

10 As the device travels along the rim of the can, the tear strip being wound upon the key 16, as indicated in Fig. 5, the material of the tear strip is wrapped about the key and causes the same to increase in diameter, thus tending to jam or wedge the key against the side of the can. This action, however, merely causes the hinged members 10 and 12 to become relatively more angularly located with respect to each other because the wind-up of the strip materials will cause the leaves to become angularly displaced relative to each other. If these leaves were rigidly connected, the key would become wedged against the side of the container and the guide means 28 would increase the frictional resistance thereof to the sliding motion of the device to such an extent that the entire device might become stuck and therefore inoperative.

20 It will be seen that this device is very easily used, it is easily applied to the tear strip and it is provided with inter-engaging means to slidably secure it to the container being opened. The hinged construction provides for easier application of the device to the container and also provides for easy sliding motion around the container, regardless of the size of the wound-up material of the tear strip, and this action will of course be impossible without the pivoted hinges as described.

30 The hinge construction 14 may be multiplied at 32 in Fig. 7, to make it easier to run the device around sharp or square corners, and the guides 34 may be impressed with hemispherical projections 36 cooperating with those at 38 to embrace the rib 40 found on the usual can for prevention of accidental escape of the opening device. In this case, the device is set on the can in tilted relation, to allow rib 40 to enter the narrow space between the projection 36 and 38, see Fig. 8.

40 Having thus described my invention and the advantages thereof, I do not wish to be limited to the details herein disclosed, otherwise than as set forth in the claims, but what I claim is:

45 1. A can opener for rimmed containers having tear strips comprising, a pair of members, a pintle, means on the members hingedly engaging the pintle so that the members are inter-pivoted thereby, said members being recessed at corresponding edges adjacent the pintle, the latter extending into the area of the recesses and being slotted inwardly from the extending end thereof whereby the slot is exposed to receive a tear strip, and the slotted portion of the pintle is generally free of the members, means on the members to slidably engage the rim of a container, and means on the pintle to rotate the same independently of the members.

50 2. The can opener of claim 1 wherein the members are arcuate in planes perpendicular to the pintle and the rim-engaging means includes a tab on each member at the concave side thereof.
